UNITED STATES PATENT OFFICE

102,870

DESIGN FOR A TOY AEROPLANE

Charles A. Brethen, Wyandotte, and John Gora,
Ecorse, Mich., assignors to All Metal Products
Company, Wyandotte, Mich., a corporation of
Michigan

Application April 4, 1936, Serial No. 61,956

Term of patent 3½ years

To all whom it may concern:

Be it known that we, Charles A. Brethen and John Gora, both citizens of the United States, residing at Wyandotte and Ecorse, respectively, in the county of Wayne and State of Michigan, have invented a new, original, and ornamental Design for Toy Aeroplane, of which the following is a specification, reference being had to the accompanying drawing forming part thereof.

Fig. 1 is a perspective view of a toy aeroplane showing our new design.

Fig. 2 is a bottom view thereof.

We claim:

The ornamental design for a toy aeroplane, as shown.

CHARLES A. BRETHEN.
JOHN GORA.
